ATION OF VIRGINIA.

ELEVATOR FEED MECHANISM FOR MAILING-MACHINES.

1,140,839.

Specification of Letters Patent.

Patented May 25, 1915.

Application filed January 91. Serial No. 089,686.

To all whom it may concern:

Be it known that I, FRANK V. MOORE, a citizen of the United States of America, and resident of Chicago, Illinois, have invented 55
a certain new and useful Improvement in
Elevator Feed Mechanism for Mailing-Ma-
chines, of which the following is a specifi-
cation.

My invention relates to mailing machines 10
of the kind in which means are provided for
folding and wrapping a magazine, and then
joining the wrapper together, and in which
an elevator feed mechanism is employed for
delivering the magazines one by one to the
15 said folding and pasting means, the said
mechanism comprising an elevator for hold-
ing and raising the stack of magazines, to-
gether with means for transferring the
magazines one by one from the top of the
20 stack to the said folding and pasting means.

Generally stated, the object of my invention
is to provide a simple and highly effi-
cient elevator feed mechanism for mailing
machines of the foregoing general character.

25 Special objects are to provide a novel
construction and arrangement whereby the
magazines are not shifted to either right or
left after leaving the top of the stack, before
reaching the said folding and pasting means,
30 and whereby each magazine leaves the top
of the stack edgewise and moves straight
ahead until it reaches the folding and wrap-
ping means; to provide a novel construction
and arrangement whereby the magazines are
35 effectively transferred from the elevator to
the conveyor by which they are delivered to
the said folding and wrapping and pasting
means of a mailing machine of this general
character; and to provide certain details and
40 features of improvement and combinations
tending to increase the general efficiency of
an elevator feed mechanism of this partic-
ular character.

To the foregoing and other useful ends,
45 my invention consists in matters hereinafter
set forth and claimed.

In the accompanying drawings—Figure 1
is a rear elevation of a mailing machine,
50 showing the same equipped with an elevator
feed mechanism embodying the principles of
my invention. Fig. 2 is a side elevation of
the mechanism, etc., shown in Fig. 1. Fig.
5 is a plan of the mechanism shown in Figs.
1 and 2. Fig. 4 is a vertical section on line
4-4 in Fig. 1. Fig. 5 is an enlarged de-
tail view of one of the devices for trans-
ferring the magazines from the top of the stack
to the so-called traveling tapes or belt con-
veyor. Fig. 6 is a side elevation of the de-
livery end of the said traveling tapes or belt
conveyor shown broken away in Fig. 4.
Fig. 7 is an enlarged view of the feed mech-
anism shown in Fig. 4. Fig. 8 is a section
on line 8-8 in Fig. 7. Fig. 9 is a section
on line 9-9 in Fig. 7. Fig. 10 is a side
elevation of the feed mechanism, showing
the same in a different position.

As thus illustrated, the mailing machine,
in connection with which my invention is de-
signed and intended to be employed, may be
of any suitable, known or approved char-
acter. As shown, an upright frame A is pro-
vided for supporting the various operative
parts of the said mechanism in suitably ele-
vated positions. At its upper end the said
frame is provided with a horizontal and
forwardly extending table a provided at
each side with guides a' for directing the
course of the magazines. The said frame
is also provided at its upper end with an
arch or cross piece a² which forms a sup-
port for certain other parts of the mecha-
nism. A shaft B is mounted transversely of
the frame at a point near the upper end
thereof, and at a point a little below the
table a, in the manner shown in Fig. 6. The
lower tapes b are two in number, and travel
around the rolls b' mounted on the shaft B,
the upper strand or horizontal portion of
each belt being disposed in position to travel
flatwise upon the said table a, whereby
these tapes or belts are adapted to support
the magazines in position for forward edge-
wise motion. These tapes or belts b are
mainly under the proper tension by the
belt tighteners b² which are disposed in the
loop or sag of each belt below the rolls b',
and which are adjustably secured on a trans-
verse shaft b³, suitably mounted on a frame.
In order that these tapes or belts may assume
this position and travel in this manner, a
shaft or roller b⁴ is provided for supporting
each tape or belt at a point directly above
the belt tighteners b², this shaft or roller
being suitably mounted on the frame. The
upper tapes or belts b⁵ are disposed imme-
diately above the similar tapes or belts b,
and are arranged to travel on rollers b⁴.

and a collarbone, buried in the soil of an
ancient grave, and which was of course
the bone of one of the body frames
of the dead. From this arrangement the
name of the grave was derived, and down about
a thousand years ago the upper portion
of the body frame and of the collarbone
remained in the grave, though the lower portion
had been removed, and the imagination passed
over the body frame as a skeleton, the upper
and lower portions being.

suitably mounted on the frame. The lower end of this arm loosely engages a pin or cross piece c^{14} by which the blocks c^3 are connected together. The shaft c^{15} is rocked or oscillated by a crank arm c^{16} secured 70 to the frame, which crank arm is in turn connected by a link c^{17} with a pivoted lever c^4 , said lever having its lower end pivoted upon the side of the frame. A cap c^5 is secured upon the outer end of the shaft C 75 and provided on its inner surface with a semi groove c^6 that engages a roll c^7 on the lever c^4 , whereby the rotation of the shaft C is employed for causing the arms c^8 to oscillate endwise. At the same time the 80 oscillation of the arm c^8 will cause these arms, to rise and fall, much as these arms are arranged to engage shoulders c^9 on the said arms. Thus the arms c^8 are given such movement that they rise and move outward, then fall or move downward at their outer ends, and then move backward to normal position. Each arm c^8 carries a tube c^{10} which is suitably connected by a flexible 85 pipe c^{11} with the main pipe c^{12} , which latter is connected with a pump which draws the air out of the pipe c^{11} , thus producing a partial vacuum in the latter. The lower end of each pipe c^{11} is provided with a self-expanding cup c^{13} for picking up the magazines and with a pivoted arm c^{14} which has 90 a hook and provided with a needle c^{15} . As shown, the cups c^{13} are disposed in pairs, each pair of cups being immediately in front of one of said needles or the direction of the 95 feed of the magazines. These pick-up 100 arms thus constructed are for picking up the magazines one by one, and for delivering the same magazine to the remaining end of the magazine.

Each arm c^3 is subject to spring tension which causes the needles to be yieldingly resilient to the magazines—that is to say, the needles are driven into the magazines by the spring tension. In this way a most positively heavy magazine can be lifted by the vacuum cups, insomuch as these cups will not be left to sit merely on the thin cover of the magazine, but to the contrary will rest on the several layers of paper which have been placed or temporarily tied together by the penetration of the needles. Thus the needles and the cups cooperate to lift up the magazines the cups doing the lifting, and the needles penetrating several layers of the paper, and thus giving the cups a steeper and stiffer body of paper to rest against. The said pick-up or lifting device composed of the vacuum cups and the needles are arranged to take the magazines from the top of a stack carried by the elevator g . This elevator is disposed in the center of the machine, and is composed of a central vertical shaft, which is adapted to receive the magazines, and a horizontal

and d^2 disposed respectively near the top and bottom of the machines, the axes of said sprockets being parallel and extending longitudinally of the machine. The link belt d is provided with a series of supporting shelves d^3 which are provided on their upper surfaces with a centrally disposed and slightly elevated rod or wire d^4 , whereby the center of each bundle of magazines resting on these shelves is slightly elevated. In this way the uppermost magazine on each shelf is always slightly humped or bulged upwardly at a point between the two pick-up or lifting devices, whereby the vacuum cups lift the magazine without any danger of the latter sagging between the two devices—that is to say, without danger of the magazine sagging at the center, which sag would tend to interfere with the proper lifting of the magazines by the vacuum cups. These shelves d^3 have notches d^5 at their forward edges through which the vacuum cups or lifting devices pass during the forward movement of said shelves in front of the receiving end of the conveyer composed of the previously described tapes or belts. These shelves are loaded at the bottom of the elevator, and the bundles of magazines resting on the shelves constitute practically one tall stack of magazines and the vacuum cups or pick-up devices take the magazines one by one from the top of the stack and feed them into the mouth of the said conveyer. Each time a magazine is taken from the top of the stack, the elevator is then operated one step to raise the stack a distance equal to the thickness of the magazine which was removed from the top thereof. This may be done in any suitable or desired manner as, for example, by means of a worm gearing d^6 applied to the lower shaft d^7 of the elevator, and controlled by a magnetic escapement device d^8 of any suitable, known or approved character. To control the said magnetic escapement device, and keep the operation of the elevator in step with the operation of the pick-up devices comprising the vacuum cups and needles, the magnets of said escapement device can be controlled by a brush and commutator device E on the shaft C through the medium of any suitable circuit arrangement. This, however, is all well known and well understood, and does not need further description, as elevators of this character were well known and well understood prior to my invention, although they were used in different relations and in a different manner relative to the conveyer.

The magazines are prevented from falling off from the shelves by the vertical strips d^9 on the frame of the machine, and by the swinging side walls d^{10} which are also mounted on the frame. When the uppermost magazine is in proper position for delivery to the conveyer, it will be found to be just above the upper ends of the vertical strips d^9 , and practically on a level with the engaging surfaces of the upper and lower tapes or belts of the conveyer. Any suitable means can be employed for preventing more than one magazine from leaving the top of the stack at a time, as, for example, a finger F disposed at the center of the rising stack of magazines, and in position to engage the end of each finger d^{11} on the shelves of the elevator, and which latter fingers support the magazines a slight distance beyond the forward edges of the shelves. In addition a blowing device G may be arranged in position in the usual and well known manner for the purpose of blowing against the underside of the magazine which is being taken off from the top of the stack, and against the edges of the magazines directly below, whereby the upper magazine will slip off easily and not carry with it any of the magazines directly below. Thus the elevator is disposed at the end of the machine, and is operated in such manner that the magazines are fed from the top of the stack directly to the end of the conveyer, and are then by the latter moved along in a straight direction. In this way the magazines do not move to either right or left from the time they enter the elevator to the time they are finally discharged from the delivery end of the conveyer. They rise in the elevator, move forward edgewise from the top of the stack, and then travel straight ahead in the conveyer.

The operations of the elevator and the other parts of the apparatus are, it will be understood, so timed that the proper feeding of the magazines from the elevator to the conveyer is accomplished with certainty and in the desired manner, and without causing the magazines to crowd together in the conveyer. An elevator feeding mechanism of this character can be used for any suitable, known or approved purpose, but, as previously explained, it is especially adapted for use in a mailing machine of that kind in which the magazines are automatically folded and wrapped with paper, and the said wrapper then pasted or sealed before being delivered from the other end of the machine.

My improved elevator feed mechanism, it will be observed, feeds the magazines in a perfectly flat condition, the back or rear edge of each magazine being ahead or in advance while the magazine is moving along in the conveyer. With this mode of operation each magazine, in a flat or unfolded condition, is discharged rear edge foremost from the delivery end of the conveyer. Each magazine travels an absolutely straight course from the time it leaves the top of the stack to the

time it reaches the delivery end of the conveyer and shoots downward. This, I find, is of advantage in various ways, and gives better results, inasmuch as the magazines are not liable to be torn or mutilated, and as the magazines are simply moved straight ahead the machine can be run at a comparatively high speed.

The transferring of the magazines from the elevator to the conveyer is an important consideration. With magazines having a pasted rear edge or back this is not so difficult, but with sewed or stitched magazines the transfer is not necessary. It is for this reason that the needles c^{24} are provided. Each needle is mounted on a block c^{25} that is pivoted in the arm c^{23} at c^{26} , which block is held in normal position by a spring c^{27} .

The arm c^{23} is pivoted at c^{28} and controlled by a rear end spring c^{29} that yields when the cup and needle strike the magazine. With this construction, the said needle has a plurality of parallel axes of motion which extend transversely of the length of the conveyer belts. The cup and needle let go of the magazine when the edge thereof is seized by the mouth of the conveyer. When the cup and needle start backward, in leaving the magazine, the needle c^{24} is deflected or swung backward against the tension of the spring c^{27} , and in this way the needle pulls out without tearing the magazine. Only a very small hole is made in the cover and one or more pages of the magazine which is not noticeable afterward. And this, in conjunction with the wires d^4 , insures a proper transfer of the magazines from the elevator to the conveyer. It is usual to punch a small hole in the top of each vacuum cup.

What I claim as my invention is:

1. In mailing machinery, mechanism for feeding the magazines, comprising a horizontal conveyer, an elevator disposed at the receiving end of said conveyer, provided with a support for raising a stack of magazines, a device for transferring the magazines one by one from the top of the stack to the said conveyer, adapted to yield for the purpose of releasing the magazine, and means for operating said device back and forth longitudinally of said machine, said conveyer being operative at any and all times to grip an oncoming magazine as soon as the forward edge thereof makes contact therewith, and before the same is released by said device whereby the yielding of said device prevents tearing of the magazine.

2. In mailing machinery, mechanism for feeding the magazine, comprising a horizontal conveyer, an elevator disposed at the receiving end of said conveyer, provided with a support for raising a stack of magazines, a device for transferring the magazines one by one from the top of the stack to the said

conveyer, adapted to yield for the purpose of releasing the magazine, said conveyer operating to grip the magazine before the same is released by said device, whereby the yielding of said device prevents tearing of the magazine, and means for operating said device back and forth longitudinally of the said machine, said device comprising a needle that pierces the magazine.

3. In mailing machinery, mechanism for feeding the magazines, comprising a horizontal conveyer, an elevator disposed at the receiving end of said conveyer, provided with a support for raising a stack of magazines, a device for transferring the magazines one by one from the top of the stack to the said conveyer, means for operating said device back and forth longitudinally of the said conveyer, said device comprising a needle that pierces the magazine, and a vacuum cup co-operating with said needle to lift the magazine, said cup and needle having a plurality of axes of movement extending transversely of the said conveyer.

4. In mailing machinery, mechanism for feeding the magazine, comprising a horizontal conveyer, an elevator disposed at the receiving end of said conveyer, provided with a support for raising a stack of magazines, a device for transferring the magazines one by one from the top of the stack to the said conveyer, adapted to yield for the purpose of releasing the magazine without tearing the same, means for operating said device back and forth longitudinally of the said conveyer, said conveyer comprising upper and lower belts between which the magazine is carried, and a floating support for the upper belt at the mouth of the conveyer, whereby the upper and lower belts are always in contact at the mouth of the conveyer to seize the edge of each oncoming magazine, before the latter is released by said device.

5. In mailing machinery, mechanism for feeding the magazines, comprising a horizontal conveyer, an elevator disposed at the receiving end of said conveyer, and at the end of the machine, provided with a support for raising a stack of magazines, a device for transferring the magazines one by one from the top of the stack to the said conveyer, means including a shaft for operating said device back and forth longitudinally of said machine, said conveyer being operative at any and all times to grip an oncoming magazine as soon as the forward edge thereof makes contact therewith, and before the same is released by said device, and means for controlling the magazines at different points in the length of the said conveyer, operatively connected with said shaft, said shaft being also provided with means for moving said device up and down.

6. In mailing machinery, mechanism for feeding the magazines, comprising a hori-

- zontal conveyor, an elevator disposed at the receiving end of said conveyor and at the end of the machine, provided with a support for raising a stack of magazines, a device for transferring the magazines one by one from the top of the stack to the said conveyor, means for operating said device back and forth longitudinally of the said conveyor and up and down, instrumentalities for keeping the escape of the magazines from the said conveyor in step with the delivery of magazines to the receiving end thereof, said means and instrumentalities including an operating shaft common thereto.
10. 7. In mailing machinery, an elevator feed mechanism comprising suction devices for lifting the magazines and means auxiliary to said devices movably connected therewith for holding two or more sheets of the magazine together to prevent injury thereto by said devices, and springs permitting said means to yield in releasing the magazine.
8. In mailing machinery, means for supporting a stack of magazines, and feed mechanism for removing the magazines from the top of the stack, said mechanism including a movable arm, a member pivoted at the end of said arm, a perforating needle pivotally mounted on said member, and springs for yieldingly holding said needle and member in operative position, carried by said arm, one spring yielding when the needle engages the magazine.
9. In mailing machinery, means for supporting a stack of magazines, and feed mechanism for removing the magazines from the top of the stack, said mechanism including a movable arm, a member pivoted at the end of said arm, a perforating needle pivotally mounted on said member, springs for yieldingly holding said needle and member in operative position, carried by said arm, and a conveyor that grips each magazine before the same is released by said needle one of said springs yielding to permit the needle to release without tearing the magazine.
10. In mailing machinery, means for supporting a stack of magazines, and feed mechanism for removing the magazines from the top of the stack, said mechanism including a movable arm, a member pivoted at the end of said arm, a perforating needle pivotally mounted on said member, springs for yieldingly holding said needle and member in operative position, and a suction device acting on the magazine adjacent said needle, carried by said arm, pivotally connected with said needle.
11. In mailing machinery, means for supporting a stack of magazines, and feed mechanism for removing the magazines from the top of the stack, said mechanism including a movable arm, a member pivoted at the end of said arm, a perforating needle pivotally mounted on said member, springs for yieldingly holding said needle and member in operative position, carried by said arm, and means for operating said device back and forth longitudinally of the said conveyor and up and down, instrumentalities for keeping the escape of the magazines from the said conveyor in step with the delivery of magazines to the receiving end thereof, said means and instrumentalities including an operating shaft common thereto.
12. In mailing machinery, means for supporting a stack of magazines, and feed mechanism for removing the magazines from the top of the stack, said mechanism including a movable arm, a member pivoted at the end of said arm, a perforating needle pivotally mounted on said member, and springs for yieldingly holding said needle and member in operative position, carried by said arm, said needle having a plurality of parallel axes of motion.
13. In mailing machinery, means for supporting a stack of magazines, and feed mechanism for removing the magazines from the top of the stack, said mechanism including a perforating needle, a conveyor which grasps the magazine before the same is released by said needle, means for permitting said needle to yield when it strikes the magazine, and means for permitting said needle to yield and thereby release without tearing the magazine.
14. In mailing machinery, means for supporting a stack of magazines, and feed mechanism for removing the magazine from the top of the stack, said mechanism including a perforating needle, a conveyor which grasps the magazine before the same is released by said needle, means for permitting said needle to yield and thereby release without tearing the magazine, and a suction device associated with and disposed in front of said needle, movably connected therewith.
15. In mailing machinery, means for supporting a stack of magazines, and feed mechanism for removing the magazines from the top of the stack, said mechanism including a perforating needle, a conveyor which grasps the magazine before the same is released by said needle, and means for permitting said needle to yield and thereby release without tearing the magazine, said needle having a plurality of parallel axes of motion extending transversely of the direction of feed, said axes permitting said needle to yield when it strikes the magazine, and when the magazine is gripped by said conveyor.
16. In mailing machinery, means for supporting a stack of magazines, and feed mechanism for removing the magazines from the top of the stack, said mechanism including a perforating needle, a conveyor which grasps the magazine before the same is released by said needle, and means for permitting said needle to yield and thereby release without tearing the magazine, said needle having parallel axes of motion, one said axis being movable about another said axis, said axes being

permitting said needle to yield when it strikes the magazine, and when the magazine is gripped by said conveyor.

17. In mailing machinery, means for supporting a stack of magazines, and feed mechanism for removing the magazines from the top of the stack, said mechanism including a perforating needle, a conveyor which grasps the magazine before the same is released by said needle, and means for permitting said needle to yield and thereby release without tearing the magazine, said needle having parallel axes of motion, a plurality of said axes being movable about another said axis, said axes permitting said needle to yield when it strikes the magazine, and when the magazine is gripped by said conveyor.

18. In mailing machinery, an elevator having magazine shelves, and a central ridge on each shelf, holding the magazines above the surface of the shelves, each ridge sloping down to the forward edge of the shelf, and means for removing the magazines from said shelves, each ridge serving to elevate the middle portion of each magazine, and thereby facilitate the operation of said means.

19. In mailing machinery, an elevator having magazine shelves, and a central ridge on each shelf, each ridge sloping down to the forward edge of the shelf, there being an extension of said ridge extending beyond said edge, and means for removing the magazines from said shelves, each ridge serving to elevate the middle portion of each magazine, and thereby facilitate the operation of said means.

20. In mailing machinery, an elevator having magazine shelves, a central ridge on each shelf, holding the magazines above the surface of the shelves, each ridge sloping down

to the forward edge of the shelf, and each shelf being inclined toward the said forward edge thereof, and means for removing the magazines from said shelves, each ridge serving to elevate the middle portion of each magazine, and thereby facilitate the operation of said means.

21. In mailing machinery, an elevator having magazine shelves, a central ridge on each shelf, holding the magazines above the surface of the shelves, each ridge sloping down to the forward edge of the shelf, and feed devices acting on the magazines on opposite sides of said ridge, as in claim 17.

22. A mailing machine having a central ridge at the center of each of a plurality of shelves, holding the magazines above the surface of the shelves, each ridge sloping down to the forward edge of the shelf, and means for removing the magazines from said shelves, each ridge serving to elevate the middle portion of each magazine, including a needle having a central axis of motion, and a plurality of said axes being movable about another said axis, the said needle being adapted to penetrate the end of said ridge, and thereby permit the removal of the magazine, and means for supporting the needle, said supporting means having a plurality of parallel axes of motion, and a plurality of said axes being movable about another said axis, the said supporting means being adapted to yield to the pull of the magazine, to prevent tearing of the magazine.

23. A mailing machine, an elevator having magazine shelves, a central ridge on each shelf, holding the magazines above the surface of the shelves, each ridge sloping down to the forward edge of the shelf, and means for removing the magazines from said shelves, each ridge serving to elevate the middle portion of each magazine, including a needle having a central axis of motion, and a plurality of said axes being movable about another said axis, the said supporting means being adapted to yield to the pull of the magazine, to prevent tearing of the magazine.

24. A mailing machine, an elevator having magazine shelves, a central ridge on each shelf, holding the magazines above the surface of the shelves, each ridge sloping down to the forward edge of the shelf, and means for removing the magazines from said shelves, each ridge serving to elevate the middle portion of each magazine, including a needle having a central axis of motion, and a plurality of said axes being movable about another said axis, the said supporting means being adapted to yield to the pull of the magazine, to prevent tearing of the magazine.
